(57) **CLAIM**

The ornamental design for a devoted medical instrument handle, as shown and described.

DESCRIPTION

FIGS. 1, 2, 3, and 4 are side elevations at 90 degree offsets of a devoted medical instrument handle showing our new design; FIG. 5 is a front to back perspective view thereof; FIG. 6 is a front view thereof; and, FIG. 7 is a back view thereof.
 The broken lines showing the remainder of the medical instrument are directed to environment and are for illustrative purposes only; the broken lines form no part of the claimed design.

1 Claim, 3 Drawing Sheets
